UNITED STATES PATENT OFFICE.

ARTHUR K. WHITE, OF ZAREPHATH, NEW JERSEY.

BATHROOM UNIT.

Application filed April 10, 1926. Serial No. 101,105.

My invention relates to a combination bath-room unit, simple in construction and easily installed at either the right-hand or left-hand side of the bath-room.

The invention consists of a combination toilet, basin and tub, or equivalent, symmetrical longitudinally and connected for mutual counterbalance, requiring but three pipe connections to the main pipe lines.

The basin frame is arranged between and supports the toilet and tub or equivalent, equilibrating the loads of the latter, and the three are preferably symmetrical with a longitudinal axis common to all three of them.

The combination unit is particularly adapted for installation by unskilled labor, in rural localities.

Referring to the drawings in which like parts are similarly designated—

Figure 1 is a plan view.

Fig. 2 a side elevation.

Fig. 3 an end elevation.

Fig. 4 is a section of the soil pipe connection, and

Fig. 5 is a modification.

The combination unit comprises a basin made entirely of the usual enamelled iron, or the frame 1 and legs 2 may be made as one piece, with a porcelain basin bowl 3 separately attached, as may be desired.

The basin has four legs 2 that stand firmly on the floor, as this is the central main load supporting member of the unit; and the basin is provided, as usual, with faucets 4, 5, arranged at the top of riser pipes 6 and 7, for hot and cold water.

Bolted to the basin frame is a cantilever toilet bowl 8, the oval seat 9 of which has its major diameter at right angles to the major diameter of the basin bowl. The toilet bowl connects with a soil pipe section 10 that is connected to the soil pipe column 11 at the floor, preferably by a slip joint 12, shown in detail in Fig. 4.

The toilet bowl 8 has a transverse flush pipe conduit 13 passing entirely across the same and closed at one end by a plug 14. The opposite end of the flush pipe conduit is connected to the flush pipe 15 leading from a flush tank 16 of any desired construction fastened to the side wall of the bath room.

By removing the plug 14 and placing it at the opposite end of the conduit, the flush

tank can be connected to and placed at the side of the unit opposite to that shown. A pipe 17 connects the tank to the cold water pipe 7 under the basin bowl.

On the opposite side of the basin frame 1 is a bath tub 18, whose rim 19 is cut-away or omitted at its straight transverse end *a* to fit with the basin frame 1 so that this straight end wall of the tub may lie against the basin frame for the purpose of enabling hooks 20 to hook in the side of the basin frame 1.

Faucet connections 21 and 22 from the water pipes 4 and 5 pass through the basin frame and tub end *a* and connect to a faucet or faucets 23. The tub is therefore supported at one end by the hooks 20 and the basin frame 1, effectually counterbalancing any load of and on the bowl 8.

The tub is provided with an overflow pipe 75 that connects to the drain pipe 25, terminating in a trap 26, which trap is connected to the soil pipe section 10 by a short pipe 27. The basin drain pipe 28 connects to this pipe 27 and is provided with the usual 80 goose-neck.

The trap 26 rests on the floor, and the only connection through the floor at the floor level will be the joint at 12, which comprises, (Fig. 4,) a brass nipple 29 threaded to the 85 end of the enamelled soil pipe section 10. This nipple has a sliding fit inside a short section 28 whose lower end is calked into the top of the soil pipe column 11, and its upper end is externally threaded for the reception of a packing gland, 29.

While some such slip connection between the soil pipe column 11 and soil pipe section 10 is preferable, it is not absolutely necessary. This connection permits the basin 95 frame to follow down with the settling of the floor, should there be any. Provision for slip of an inch more or less will be sufficient.

It will be seen that the unit is symmetrical with respect to a centre line B—B common to the three elements, toilet, basin and tub or similar device, so that the combination may be positioned with either side against a bath room wall, with the tub or equivalent counterbalancing the toilet bowl.

In Fig. 5, in lieu of a tub 18, I have shown a shower pool 30 hooked to the basin frame 1 by hooks 20, the hot and cold water pipes 6 and 7 having transverse branches at 31 containing the shower valves 32 that control

the water to the pipe 33 terminating in the rose-head 34 which is surrounded by the customary curtain support 35.

Of course it will be understood that in lieu of hooks 20, bolts or other fastening means may be used for connecting the tub, pool or the likes to the basin frame 1, but hooks are more simple and more easily used.

The tub need have but two legs, at the end furthest from the basin frame, which latter takes the load through the hooks 20 or equivalent, that would be taken by the other two legs were they present, and this load counterbalances any tipping action from the toilet bowl.

I claim—

1. A plumbing unit comprising separate bath room fixtures connected to one another, and comprising a stationary toilet, a stationary tub and a stationary basin frame between the toilet and tub and supporting both the toilet and tub, and the toilet counterbalancing part of the load of the tub on the frame.

2. A plumbing unit comprising separate bath room fixtures connected to one another and comprising a stationary basin frame, a stationary toilet connected to and supported on one side of said frame, and a tub connected to and supported on one end on the other side of the frame, said basin, tub and toilet being in axial alinement to permit either side of the unit to be arranged along a wall.

3. A plumbing unit comprising a separate stationary basin frame and toilet, means connecting the toilet to one side of the basin frame for support thereby, a soil pipe beneath said frame to which both basin and toilet are connected.

4. A plumbing unit comprising a separate stationary basin and frame therefor extending to the floor and open at the front and

back, and a toilet secured to the side of the frame and supported thereby, a soil pipe beneath the basin and pipe connections beneath the basin between the toilet and basin and the soil pipe, said connections being above the floor level, and the basin and toilet being symmetrical with respect to a line common to both of them.

5. A plumbing unit comprising a separate stationary basin frame and tub, means to detachably connect the outlet end of the tub to the frame to support said end on the frame, a soil pipe connection for the tub and for the basin, both beneath the frame.

6. In a plumbing unit comprising a toilet, basin and tub connected as a unit; a soil pipe section from said toilet extending beneath the basin, and drain pipes from tub and basin, all above the floor level, and a slip connection for connecting the soil pipe section to the soil pipe at the floor level.

7. In a plumbing unit, a basin, a cantilever toilet bowl supported thereby at one side thereof, a tub connected to the opposite side of the basin, a soil pipe section from said bowl substantially all above the floor level and extending beneath the basin, and trapped drain connections between said tub and basin and said section, all above the floor level.

8. A plumbing unit comprising a basin, a cantilever toilet bowl supported on one side of the basin, a bath tub having means at one end to support it on a floor and hooks at its opposite end engaging the opposite side of the basin, said basin, bowl and tub being in symmetrical alinement, a soil pipe below the basin, and connections from said bowl, basin and tub to said pipe above the floor level.

In testimony that I claim the foregoing as my invention, I have signed my name hereto.

ARTHUR K. WHITE.
